(57) CLAIM

The ornamental design for a shirt as shown and described.

DESCRIPTION

Shirt

1.1: Perspective; of a first embodiment;

1.2: Front, as shown in FIG. 1.1;

1.3: Back, as shown in FIG. 1.1;

1.4: Left, as shown in FIG. 1.1;

1.5: Right, as shown in FIG. 1.1;

1.6: Top, as shown in FIG. 1.1;

1.7: Bottom, as shown in FIG. 1.1;

2.1: Perspective; of a second embodiment;

2.2: Front, as shown in FIG. 2.1;

2.3: Back, as shown in FIG. 2.1;

2.4: Left; as shown in FIG. 2.1;

2.5: Right; as shown in FIG. 2.1;

2.6: Top, as shown in FIGS. 2.1; and

2.7: Bottom, as shown in FIG. 2.1.

The broken lines for the collar area in the figures are for the purpose of illustrating portions of the shirt that are not part of the claimed designs.
